UNITED STATES PATENT OFFICE.

JAMES H. BOYE, OF CHICAGO, ILLINOIS, ASSIGNOR TO THE BOYE NEEDLE COMPANY,
OF CHICAGO, ILLINOIS, A CORPORATION OF ILLINOIS.

RIBBON-LEADER.

1,161,448.

Specification of Letters Patent.

Patented Nov. 23, 1915.

Application filed December 14, 1914. Serial No. 877,102.

To all whom it may concern:

Be it known that I, JAMES H. BOYE, a citizen of the United States, residing at 4348 Ravenswood avenue, Chicago, in the county of Cook and State of Illinois, have invented a new and useful Improvement in Ribbon-Leaders, of which the following is a specification.

My invention relates to an improvement 10 in the class of devices for leading or threading ribbon through fabric.

In the accompanying drawing, Figure 1 is a perspective view of my improved ribbon-leader in its open condition, the view 15 also showing a ribbon-end ready to be inserted and clamped between the jaws of the device; Fig. 2 is a plan view of the device, in its closed condition, with an end of a ribbon shown, by dotted representation, to 20 be clamped between the jaws of the device ready to be threaded; Fig. 3 is a section on line 3, Fig. 2, and Fig. 4 is a section on line 4, Fig. 1.

All the views show the device in much 25 larger size than it is provided for use.

The body 5, forming the needle of the device, which is best made of an adequately stiff, flat strip of sheet-metal, is bent upon itself to form the point 6, toward which the 30 needle tapers from its opposite end. The bent section 7 is riveted near its rear end to the body, and the rivet fastens at one end a leaf-spring 8, shown to be provided on the under side of its forward end with barbs 9 35 to register with holes 9^a in the adjacent end of the needle. An arm 10, shown in its preferred longitudinally curved form, is pivoted midway between its ends to a flat side of the needle. The pivot passes through the 40 spring 8, which curves upwardly toward its barbed end from the pivot-point to form a resilient jaw for coöperating with the adjacent section of the body, forming a companion-jaw in clamping an end of a piece 45 of ribbon 11, tape or the like, to be threaded or led through fabric by manipulating the device. The ends of the arm, which is preferably resilient, but less so than the jaw 8, are shown rounded and tapered; and the 50 arm is so pivoted that when it is turned in either direction to lie parallel with the face of the needle, the part then extending from the point toward the section 7 will reach at its rounded and tapered end underneath the 55 adjacent end of that section, where it is

shown to form a recess at 7^a to receive and house that end.

With the device in the condition in which it is represented in Fig. 1, a ribbon 11 to be threaded through fabric is inserted between the jaws, whereupon the arm 10 is turned to the position shown in Fig. 2, whereby one section bears against the spring jaw to force it toward the companion-jaw and clamp the ribbon-end between the jaws, where the 60 barbs 9 penetrate and hold it firmly. The other section of the arm, by housing itself in the recess 7^a, prevents any obstruction being presented in the direction of working the device through the fabric to lead the 65 ribbon through the same; and the opposite rounded end of the arm prevents the latter from catching in the fabric, in the event of the arm accidentally getting out of parallelism with and projecting at its ends laterally 70 beyond the body 5, since the fabric will then smoothly guide that end. When the ribbon to be threaded is wider than the implement, its end may be folded into a point, as represented in Fig. 1, to center the ribbon-end between the clamping-jaws and cause true 75 leading of the ribbon in working it through the fabric.

I realize that considerable variation is possible in the details of construction thus specifically shown and described, and I do not intend by illustrating a single specific or preferred embodiment of my invention to be limited thereto; my intention being in the following claims to claim protection upon 80 all the novelty there may be in my invention as broadly as the state of the art will permit.

What I claim as new and desire to secure by Letters Patent is:

1. A device of the character described, 85 comprising a needle, a movable jaw secured on one face of the said needle to extend toward the rear end of the latter and form therewith clamping jaws, and an arm pivoted to the said needle to swing in alinement 90 with said jaws and over the said movable jaw to press the latter toward its companion 95 jaw.

2. A device of the character described, 100 comprising a needle, a spring-jaw secured on one face of the needle to extend toward the rear end of the latter and form therewith clamping jaws, a pivot stud extending 105 through said spring and needle, and an arm pivoted between its ends on said stud to press 110

the spring-jaw toward the companion-jaw by turning the arm on its pivot in the direction to extend parallel with the needle.

3. A device of the character described, comprising a needle provided with a hole in its rear end, a spring-secured on one face of the needle to extend toward said rear end and form therewith a pair of clamping-jaws, a prong on the spring-jaw to enter said hole, 10 a pivot stud extending through said spring and needle, and an arm pivoted between its ends on said stud to press the spring-jaw toward the companion-jaw by turning the arm on its pivot in the direction to extend 15 parallel with the needle.

4. A device of the character described, comprising a strip bent upon itself and forming the pointed end of a needle, the bent section being fastened near its rear end to 20 the body of the needle and forming therewith a recess, a flat spring fastened at one end to the needle near the rear end of said bent section to extend toward the rear end of said body and form therewith clamping-jaws, a pivot stud extending through said 25 spring and needle, and an arm pivoted be-

tween its ends on said stud to press the spring-jaw toward the companion-jaw by turning the arm on its pivot in the direction to extend parallel with the needle.

30

5. A device of the character described, comprising a strip bent upon itself and forming the pointed end of a needle, the bent section being fastened near its rear end to the body of the needle and forming therewith a recess, a flat spring fastened at one end to the needle near the rear end of said bent section to extend toward the rear needle-end and form therewith clamping-jaws, 40 a pivot stud extending through the spring and the needle body, and an arm having rounded ends pivoted midway between the latter on said stud to press the spring-jaw toward the companion-jaw by turning the arm on its pivot in the direction to extend parallel with the needle and enter into said recess its adjacent end when so extended.
